(57) **CLAIM**

I claim the ornamental design for a range hood, as shown and described.

DESCRIPTION

FIG. 1 is a top plan view of a first embodiment of a range hood, showing my new design;

FIG. 2 is a front elevational view of the embodiment of FIG. 1;

FIG. 3 is a bottom plan view of the embodiment of FIG. 1;

FIG. 4 is a right side elevational view of the embodiment of FIG. 1, the left side being a mirror image of the right side;

FIG. 5 is rear elevational view of the embodiment of FIG. 1;

FIG. 6 is a perspective view of the embodiment of FIG. 1;

FIG. 7 is a front view of the second embodiment of a range hood, showing my new design;

FIG. 8 is a right side elevational view of the embodiment of FIG. 7, the left side being a mirror image of the right side;

FIG. 9 is a rear elevational view of the embodiment of FIG. 7; and,

FIG. 10 is a perspective view of the embodiment of FIG. 7.
